DESIGN FOR A SPECTACLE FRAME

Harris King Halikman, Lynn, Mass., assignor to American Optical Company, Southbridge,
Mass., a voluntary association of Massachusetts

Application December 9, 1940, Serial No. 97,181

Term of patent 14 years

To all whom it may concern:

Be it known that I, Harris King Halikman, a citizen of the United States of America, residing at Lynn, in the county of Essex and State of Massachusetts, have invented a new, original, and ornamental Design for a Spectacle Frame, of which the following is a specification, reference being made to the accompanying drawing, forming a part thereof.

Fig. I is a perspective view of a spectacle frame showing my new design, the essential features of which are shown in full lines; and

Fig. II is a top plan view thereof.

I claim:

The ornamental design for a spectacle frame, substantially as shown and described.

H. KING HALIKMAN.
